EGG COOKER

Samuel J. Mann, Inglewood, N.J., assignor to Salton,
Incorporated, New York, N.Y., a corporation of New York

Filed Mar. 24, 1969, Ser. No. 16,397

Term of patent 14 years

Int. Cl. D7—02

U.S. Cl. D44—1

FIG. 1 is a front elevational view of an egg cooker embodying my new design;

FIG. 2 is a right side elevational view thereof;

FIG. 3 is a top plan view thereof;

FIG. 4 is a rear elevational view thereof; and

FIG. 5 is a bottom elevational view thereof.

I claim:

The ornamental design for an egg cooker, substantially as shown.
